UNITED STATES PATENT OFFICE.

SEWARD S. BABBITT, OF PITTSBURG, PENNSYLVANIA, ASSIGNOR OF ONE-HALF TO HENRY AIKEN, OF SAME PLACE.

CRANE.

SPECIFICATION forming part of Letters Patent No. 484,870, dated October 25, 1892.

Application filed June 13, 1892. Serial No. 436,476. (No model.)

To all whom it may concern:

Be it known that I, SEWARD S. BABBITT, of Pittsburgh, in the county of Allegheny and State of Pennsylvania, have invented a new and useful Improvement in Cranes, of which the following is a full, clear, and exact description, reference being had to the accompanying drawings, in which—

Figure 1 is a side elevation of a charging-crane constructed in accordance with my invention. Fig. 2 is a plan view, on a larger scale, of part of the apparatus. Fig. 3 is a vertical cross-section on the line III III of Fig. 1, but on a larger scale.

Like symbols of reference indicate like parts in each.

The object of my invention is to provide improved means for manipulating ingots, blooms, and other articles for the purpose of charging and withdrawing the same from furnaces; but I desire to premise that the invention is not limited to any special use to which the apparatus may be put, nor to the precise construction shown in the drawings, which may be modified in various ways within the scope of the claims.

My improved apparatus comprises a crane, preferably a rotatory crane, having a jib or carrier, a trolley mounted thereon, a peel or gripper carried by the trolley, mechanism for turning the peel or gripper radially, and mechanism for turning it axially for the purpose of tipping the metal piece or burden. These parts are of peculiar and novel construction, and the especial features which I claim as of my invention are summarized in the following claims.

In the drawings, 2 represents the rotatory mast of a crane provided with my improved mechanism.

3 is the jib, which projects radially from the mast, as shown, and is preferably composed of separated parallel beams, as shown in Fig. 3. The trolley is composed, preferably, of two sets of trucks or carriages 4 5, mounted on the jib and having wheels bearing thereon both above and below the beams. These trucks are connected together, as shown, and are moved back and forth on the jib by the action of a hydraulic cylinder 6,

Fig. 1. Each of the trucks or carriages is preferably composed of two horizontally-divided parts connected by a bolt or bolts 7, the upper parts having wheels which ride on the jib and the lower parts having bearings on the under side of the jib and supporting the metal-carrying mechanism, hereinafter described. The purpose of this construction is to simplify the manufacture of the trucks and to enable the parts to be tightened together in case of wear.

From the truck or carriage 5 is suspended a vertically-swiveled frame which affords the main support for the grippers and is provided with means for rotating it axially, and from the other truck is suspended the track by which the gripping mechanism is supported during its radial motion. This division of the trolley into two separate trucks or carriages is for many reasons convenient and desirable; but the invention is not limited thereto.

The vertically-swiveled frame above mentioned is constructed as follows: A frame or platform suspended from the truck 5 has at its lower end a circular base-plate 10, having a marginal flange 11, which fits over the circular head 12 of an upright frame 13. A vertical bolt 15 extends up from the frame 13 and through a socket on the plate 10, and is provided at its upper end with a nut 16, which holds the parts together. The part 15 thus serves the function of a king-bolt or axis for the swivel-frame 13. In order to rotate said frame, I fix to the bolt 15 a pinion 17, with which meshes the toothed rack 18 on the plunger of a hydraulic cylinder 19, set on the plate 10. On projecting this plunger the engagement of the rack with the pinion rotates the bolt 15, and thus turns the frame 13 on its vertical swivel-axis. The lower part of the frame 13 is forked vertically and is shaped to afford separated bearings 20. The grippers shown in the drawings consist of a bar 21, having at the end a gripping-head 22, and opposite thereto a sliding or otherwise movable head 23. As shown in the drawings, the head 23 is movable longitudinally on the bar 21 toward and from the head 22, so as to engage or release an interposed metal bloom 100.

or ingot. To activate the head 23, I employ a motor, consisting, preferably, of two parallel hydraulic cylinders 24, bolted together and connected by a rod 25 with a gripper-bar 21. The connection of the bar 21 with the rod 25 is preferably by means of a hinged joint 26, constructed, as shown, so as to afford to the gripper-bar upward pivotal motion, but to sustain it from moving downwardly, the purpose being to permit the gripper-bar to yield somewhat when in lowering the crane-jib the burden of the crane is deposited upon the ground. The plungers 27 of the cylinders 24 are connected to the head 23, so that by projecting or retracting them the head is moved longitudinally on the gripper-bar, and in order that such connection may not interfere with the movement of the bar 21 on its hinge-joint it is constituted by an open-bottom fork 23', fixed to the head 23, fitting on the plunger 27 and bearing against the rear of a head 27' on the latter. In order, also, to prevent injury to the apparatus if in lowering the jib the bearings 20 or other parts should strike the ground, I connect the jib to the mast by a pivotal connection 3' and form a loose link or slotted connection 4' in the usual diagonal jib-strut. With this construction the jib can yield vertically on the pivot 3', the connection 4' permitting its upward motion.

The rod 25 and the plungers 27 pass through a journal-block 28 within the bearings 20, and between said bearings on the journal-block there is fitted a toothed pinion 29 in gear with the rack 30, fixed to the plunger 31 of a hydraulic cylinder 32, which is carried by the frame 13, Figs. 1 and 3. By projecting or retracting said plunger the pinion is rotated, and thus the journal-block 28, the grippers, and the cylinders are caused to turn on their longitudinal axes. Thus by means of the cylinder 32 the grippers may be rotated axially, and by the cylinder 19 the frame 13 may be turned on its vertical axis, thus causing the grippers and the cylinders 24 to swing radially in a horizontal plane.

To support the cylinders 24 and their connected parts and to guide them during such radial motion, the following mechanism is employed: 33 is a curved track composed of parallel separated beams suspended from the truck 4 by a frame composed of hangers 34. A flanged wheel 35 is journaled in a bearing formed on a prolongation of the rod 25 and is set between the beams of the track 33. The radius of curvature of the track is the distance between the wheel and the vertical axis of the frame 13, so that as said frame is turned the wheel will constantly ride on the track and will brace and support the gripper and its actuating-cylinders. The valves controlling the water-supply pipes of the several cylinders may be supported by the frame 34, together with the seat of the workman who operates the same. This being a common construction, it is not specifically illustrated.

As thus constructed the operation of the apparatus in delivering metal to and removing it from the furnace is as follows: To lift the metal from the floor of the mill or other support on which it may be resting, the jib may be lowered in the manner usually employed in crane mechanism, and the grippers may be brought into position to grasp the same by projecting the trolley on the jib (which projection will move both the track 33 and the frame 13) and by rotating the frame on its vertical axis. The metal may then be grasped by moving the head 23 on the bar 21, and then by raising the jib, turning it radially to the proper position, turning the frame 13 so as to bring the grippers into line with the furnace-door, and, projecting the trolley, the metal may be delivered to the furnace. The operations of withdrawing metal from the furnace are performed in reverse order.

The advantages of my invention will be appreciated by those skilled in the art. As before intimated, the construction and arrangement of the parts may be changed somewhat without variance from the scope of my invention as stated in the following claims.

I claim—

1. The combination of grippers, a motor for operating them, and mechanism adapted to rotate the grippers and motor axially, substantially as and for the purposes described.
2. The combination of grippers, a bearing permitting axial rotation thereof, and a gripper-actuating motor connected with the grippers through the bearing, substantially as and for the purposes described.
3. The combination of grippers, a bearing permitting axial rotation thereof, a gripper-actuating motor connected with the grippers through the bearing, and a motor adapted to effect such axial rotation, substantially as and for the purposes described.
4. The combination of grippers, separated bearings permitting axial rotation thereof, and a motor having a power connection with the grippers between the bearings, substantially as and for the purposes described.
5. The combination of a jointed gripper-bar, a gripper-head, an actuating-motor, and a freely-detachable connection between the actuating-motor and the head, substantially as and for the purposes described.
6. The combination of a frame having a circular base, a second interfitting frame set below the same and vertically swiveled thereto, a metal support carried by the second frame, and a motor on the first-named frame mechanically connected with the swiveled frame and adapted to rotate the same, substantially as and for the purposes described.
7. The combination of a frame having a circular base, a second, interfitting frame set below the same and vertically swiveled thereto, a metal support carried by the second frame, and a motor on the first-named frame mechanically connected with the swiveled

frame and adapted to rotate the same, a jib, and a trolley which is mounted on the jib and which carries the said frames and metal support, substantially as and for the purposes described.

8. The combination of a jib or carriage, a trolley mounted thereon, a frame carried by the trolley, a second frame vertically swiveled thereto, axially-rotatory grippers, and a rotating motor carried by the second frame, a second motor adapted to rotate said frame on its swivel-axis, and gripper-actuating mechanism, substantially as and for the purposes described.

9. A crane-trolley formed of horizontally-divided parts and having upper and lower wheel-bearings on the jib, a motor adapted to move it vertically, and means for drawing said parts together, substantially as and for the purposes described.

10. The combination of a metal support or grippers, a vertically-turning support therefor, a track by which the metal support or grippers is upheld during its radial motion, a jib or carrier, and means by which said turning support and track are movable on the jib

or carrier, substantially as and for the purposes described.

11. The combination of a metal support or grippers, a vertically-turning support therefor, a track by which the metal support or grippers is upheld during its radial motion, a jib or carrier, a trolley by which said turning support and track are carried, and a motor for moving the trolley, substantially as and for the purposes described.

12. The combination of a vertically-turning frame, a metal support or grippers rotatory in bearings thereon, a motor carried by said frame and adapted to rotate the metal support or grippers, an upper frame to which said turning frame is swiveled, and a motor mounted on the upper frame and connected with the turning frame, substantially as and for the purposes described.

In testimony whereof I have hereunto set my hand this 4th day of June, A. D. 1892.

SEWARD S. BABBITT.
